PULSE TRANSMITTER

Walter van B. Roberts, Princeton, N. J., assignor
to Radio Corporation of America, a corporation
of Delaware

Application August 1, 1942, Serial No. 453,170

11 Claims. (Cl. 250—17)

1

This invention relates to improvements in pulse transmission systems.

An object of the present invention is to provide an improved method of and apparatus for modulating the timing of successive pulses in a pulse type transmitter.

Another object is to modulate the timing either from a phase or frequency standpoint of non-sinusoidal waves without varying the timing of the generator of said waves.

A more specific object is to provide a modulating system which includes a source of constant frequency waves, a non-reflecting load, a line connected between the source and the load, and reactance tube network means connected across the line and arranged to control the timing of arrival of waves at the load, with means for compensating for attenuation of the waves by circuits of the reactance tube network means.

An exposition of the principles underlying the present invention will now be given: It is known to employ reactance tube circuits which include a multi-electrode vacuum tube having a condenser connected between the anode and the control grid and a resistor connected between the control grid and the cathode of the tube. A variable reactance can thus be obtained across the anode and cathode which constitute, in effect, terminals for the circuit. It is known that such a combination behaves with respect to a sinusoidal voltage applied to the aforesaid terminals like a combination of capacity and resistance whose magnitudes may be varied by varying the biasing potential of the control grid of the tube. I have found, however, that this behaviour is not limited to sinusoidal waves and that such a reactance tube system behaves like a combination of capacity and resistance with respect to waves of any shape whatsoever impressed upon the network terminals. A similar result is reached for other reactance tube systems employing phase shifting elements of other natures than the capacity-resistance combination which is discussed above by way of illustration.

Inasmuch as the reactance tube network described behaves like a combination of capacity and resistance, it is now proposed in accordance with the invention to connect a sufficient number of such reactance tube networks across a transmission line to effectively control the velocity of propagation of waves along said line by varying the effective distributed shunt capacity across the line. However, since each of these networks introduces a resistance component as well as a capacity component across the line,

2

waves traveling along the line will suffer attenuation as well as variations of velocity of propagation. To avoid this undesired attenuation, it is proposed in accordance with the invention to introduce a time delay between the arrival of waves at the phase shifting portion of the reactance network and the arrival of the waves at the anode-cathode terminals of the tube. The action of the complete network of the invention is best described with reference to the accompanying drawing, of which:

Fig. 1 shows, by way of example only, one embodiment of the present invention; and

Fig. 2 shows, graphically, the timing variation 15 of pulses traveling along the system shown in Fig. 1.

In Fig. 1, there is shown a pulse transmitter system which includes a blocking oscillator 1 adapted to generate relatively widely spaced 20 pulses of constant amplitude and frequency, which are fed into a concentric transmission line 2 for subsequent utilization by a transmitter 4 and antenna 5. In series with the line 2 and forming part thereof there are provided loops or 25 adjustable length folded portions 3, 3, and another line 2'. The folded portions 3 are shown in the form of lecher wire lines with adjustable sliders, by way of example. The transmitter 4 is adapted to convert energy pulses received from 30 line 2 into corresponding pulses of ultra high frequency waves and to radiate these waves from antenna 5. A number of identical reactance vacuum tube circuits 12 are connected across the terminals 9 and 11 of the folded portions 3 and 35 the outer conductor of the transmission line. Each of these networks comprises a phase shifting circuit which includes capacity 6 and resistor 7 in series, and by-pass condenser 8. One armature of condenser 6 is connected to terminal 9 while the other armature of this condenser is connected to the control grid of the reactance tube intimately associated therewith. The resistor 7 and by-pass condenser 8 are connected in series between the ground lead of the cathode 40 and the control grid. This phase shifting network produces a voltage across resistor 7 as a result of voltage at terminal 9 of folded line portion 3. The anode 10 of the reactance tube is connected to the other terminal 11 of the folded part 3 so that anode current produced by the aforesaid grid voltage occurs earlier with respect to the arrival of a traveling pulse the longer the folded part 3 of the line. The result of this is that the anode current pulse may be analyzed 45 into not only a wattless or energy-less compo-

The grid potential for each of the reactance tubes is obtained from lead 13 extending to a single source of modulating voltage which might, for example, be audio frequency. In this case, the pulses arriving at the transmitter 4 will be phase modulated in accordance with audio voltage. However, it is well known that the audio voltage may be suitably predistorted so that the pulses arriving at transmitter 4 are frequency modulated with respect to the original voltage prior to distortion.

Fig. 2 represents along the upper line A the series of constant amplitude-constant frequency pulses impressed by the blocking oscillator 1 on the left hand end of transmission line 2. Along the line B, directly beneath, are shown the pulses arriving at transmitter 4. It should be noted that these pulses on line B are of unchanged amplitude but that their spacing is altered as illustrated so that while the average frequency of arrival is the same as the frequency of the blocking oscillator, yet their momentary phase or frequency of arrival is alternately greater and less than that of the blocking oscillator. In the lowest line C of Fig. 2 are shown the pulses of ultra short waves radiated from antenna 5, which pulses are substantially identical in position and length but occur with variable frequency determined by the frequency of the pulses shown in the line B immediately above.

It will be appreciated that by the use of the present invention, it is not necessary to modulate the operation of the blocking oscillator in any respect to obtain a modulation of the pulses, as a result of which the construction of such an oscillator is greatly simplified. Furthermore, in view of this advantage of the invention, the blocking oscillator may be operated under crystal control for improved stability.

It will also be realized that the phase shifting circuit connected across the transmission line 2 at point 9, for example, can take other specific forms than that illustrated. The object of the

invention will be achieved so long as the effective velocity of propagation along the line is capable of being varied by the application of modulating potential to the grid of the reactance tube. It will be appreciated that the phase or frequency modulated pulses emanating from transmission line 2' may be employed for other purposes than to excite ultra high frequency radiation, if desired. In the drawing, direct current energizing voltage for the anodes of the tubes has been shown supplied by means of a shunt feed choke coil, while a blocking condenser forms the alternating current connection between anode and line. Other arrangements may, of course, be substituted for energizing the various tube electrodes with direct voltages.

The term "non-sinusoidal" used in the appended claims is intended to designate any shape pulse other than a continuous sinusoidal wave.

What is claimed is:

1. In a transmission system, a source of non-sinusoidal wave pulses, a transmission line connected to said source for feeding said pulses to a load, means for relatively displacing the positions of said pulses on said line comprising a phase shifting circuit shunted across said line, a vacuum tube excited from said phase shifting circuit, and a connection from the output of said tube to said line at a point displaced along said line from the point of connection of said phase shifting circuit, whereby the energy component of anode current fed into said lines reduces the energy losses of said waves traveling along said line while the energy-less component acts effectively to shift the position of said wave along said line.

2. A pulse transmitter comprising a source of non-sinusoidal wave pulses, a transmitter of ultra short waves, and a transmission line extending between said source and transmitter, a plurality of physically spaced adjustable line sections inserted in series at different locations along said line, a reactance tube network across the terminals of each adjustable line section corresponding to the junction points to said line, and a connection from the control electrodes of said reactance tube networks to a common source of audio frequency modulating potential.

3. A pulse transmitter comprising a source of substantially rectangular wave pulses, a transmitter, a line connection between said source and said transmitter, a plurality of lecher wire lines inserted in series with said line at different locations along said line, a slider for each lecher wire line for adjusting the effective length thereof, a reactance tube network connected across the junction points of each lecher wire with said line, each of said networks including a vacuum tube having a grid, an anode and a cathode, a reactance connected between the grid of each tube and that junction point of its associated lecher wire line nearest said source, a resistance connecting said reactance to the cathode through a by-pass capacity, a connection from the anode of each tube to the other junction point of its associated lecher wire line which is nearest the transmitter, and a connection from the grid of each tube to a common source of modulating voltage, whereby the energy component of anode current fed into said line by said first source reduces the energy losses of the waves traveling along the

- line.

4. A pulse transmitter comprising a source of pulses, a utilization circuit, a line connected between said source and utilization circuit, and a reactance tube network connected to spaced

points on said line and having a source of modulating voltage connected thereto for varying the relative timing of the pulses along said line, said network including a phase shifting circuit and a vacuum tube.

5. A pulse transmitter as defined in claim 3, characterized in this that said reactance is a condenser.

6. A pulse transmitter in accordance with claim 2, characterized in this that said networks are uniformly distributed along said line.

7. A pulse transmitter comprising a source of non-sinusoidal wave pulses, a transmitter of ultra short waves, a transmission line extending between said source and transmitter and having a folded portion, a reactance tube network across the terminals of said folded portion, said network including a phase shifting circuit and a vacuum tube, and a connection from a grid of said tube to a source of audio modulating voltage.

8. A pulse transmitter comprising a source of non-sinusoidal wave pulses, a utilization circuit, and a transmission line extending between said source and utilization circuit, a plurality of physically spaced adjustable line sections inserted in series at different locations along each wavelength of said line, a reactance tube network across the terminals of each adjustable line section corresponding to the junction points to said line, and a connection from the control electrodes of said reactance tube networks to a common source of modulating potential.

9. A pulse transmitter comprising a source of non-sinusoidal wave pulses, a utilization circuit, a transmission line extending between said source and utilization circuit and having a folded portion, a reactance tube network across the terminals of said folded portion, said network including a phase shifting circuit and a vacuum tube, and a connection from a grid of said tube to a source of audio modulating voltage.

10. The method of operating a transmission system including a transmission medium, which comprises generating pulses of a substantially constant frequency, transmitting said pulses over said transmission medium, affecting said medium at a plurality of spaced points in accordance with signal modulation to thereby vary the velocity of propagation of said pulses through said medium, and simultaneously increasing the energy of the pulses traveling over said medium.

11. A transmitter comprising a source of non-sinusoidal waves, a utilization circuit, a transmission line extending between said source and utilization circuit, a circuit providing a delay path for waves passing thereover connected between two spaced points on said line, a reactance tube network across the terminals of said circuit, said network including a phase shifting circuit and a vacuum tube, and modulating means coupled to an electrode of said tube.
